ABSTRACT: The invention provides a lower member or buck of a garment pressing machine which is so constructed that adequate space is provided for turning of a jacket or coat whose shoulders and parts about the armholes are being pressed, the buck being cantilevered on a curved or angularly shaped post which is constructed of heavy steel plate and is hollow, the post housing the stem supply and its return, as well as including a passage for cooling air leading from the perforated top plate of the buck to a connection to a vacuum pump. The upper member of the buck is constructed to provide a space for the entry of heating steam from within the post and also a connection between the space immediately below the perforated top plate and the air passage in the post, re-enforcements being provided to enable the top member to withstand the shock and pressure of the usual head of the pressing machine. In the preferred construction, the post is of approximately triangular cross section and tapered upwardly, a tubular steam and condensate return forming a vertex of the triangle.

FIG. 2

FIG. I

FIG. 3

INVENTOR:
SAM GOLDSTEIN

ATTORNEY

BUCK FOR PRESSING MACHINES

The present invention relates to the lower member or buck of a garment-pressing machine, more particularly of a machine for pressing the shoulders and parts about the arm-holes of jackets and coats, known also as an "armhole creaser."

It is an object of the invention to provide a buck which is supported in cantilever fashion at approximately an end thereof by a curved or bent hollow post, whereby adequate unobstructed free space is provided below the buck for turning a jacket or coat whose shoulders and parts about the arm-holes are being pressed, while at the same time providing in its hollow interior adequate space for the supply and return of heating steam for the buck, and also for a vacuum connection to the space immediately below the perforated top plate of the buck for drawing cooling and drying air through the pressed garment parts.

It is also an object of the invention to provide a buck whose top member is supported in cantilever fashion on a curved or bent and preferably tapered hollow post which is welded to steel beam reinforcing and partitioning structure within such top member and having separate mutually sealed sections thereof debouching into the steam and vacuum chambers of the top member.

It is a further object of the invention so to construct and arrange the supporting post of the buck that it is secured to the base over an area extending rearwardly of the vertical projection of the buck on the base, so that there is available a free unobstructed space below the top member of the buck for substantially the whole length thereof, whereby the gathering and turning of the parts of the garment not being pressed at any moment can take place with facility and expedition.

Another object of the invention is to provide a compact supporting post which at the same time provides the passageways for the heating steam and for the return steam and condensate, and also for the cooling and drying air, the post being constituted principally of a tube to which opposite walls of the post are welded, the walls being joined at their other ends by a transverse plate to enclose the suction space which is connected to the suction pump of the complete apparatus.

It is a still further object of the invention to provide a compact supply post which is of approximately triangular form with the steam supply and condensate return embodied in a tube which forms a forwardly directed vertex of the triangular structure, whereby the remaining cross-sectional area of flow can be allotted to the vacuum or suction space for drawing cooling air through the heated garment on the buck.

Further objects and advantages of the invention will be apparent to those skilled in the art from the following more detailed description thereof, taken together with the accompanying drawing in which:

FIG. 1 is a side elevation of my improved buck and its supporting structure, the same being partly in section to reveal the internal construction;

FIG. 2 is a plan view of the top member of the buck with the perforated top plate removed; while

FIG. 3 is a section along the line 3-3 of FIG. 1.

Referring to the drawing, there is shown at 10 the steel base of my improved buck which is connected to a hollow angular (by which term, I include also curved) post 11, preferably by welding, as indicated at 12. The upper end of the post is connected, preferably also by welding, as indicated at 13, to the steel bottom plate 14 of the top member 15 of the buck, and also internally of such member, as will be described hereinafter.

The post is formed of heavy steel plates, of the order of thickness of three-eighths inch, welded together, and encloses a sealed space which contains a steel pipe 16 for steam condensate return, and within which is disposed, in spaced relation, a steam supply pipe 17, which is preferably of brass.

Between the pipe 16 and the closed rear wall 11c of the post is a space 18 which is connected to a vacuum pump, as will be explained more fully hereinafter.

In the illustrated preferred form of my invention, the steel pipe 16 forms the forwardly directed vertex of the approximately triangular outline of the horizontal cross section of the post, as shown in FIG. 3. To the pipe there are welded the sidewalls 11a and 11b of the post which flare outwardly from the pipe (FIG. 3), the other ends of the walls being sealed by the end wall 11c which is welded thereto, as indicated at 11d.

The top member 15 of the buck includes, in addition to the bottom plate 14, also a top plate 19 spaced therefrom and perforated, as indicated at 20, in the usual manner for the entry of cooling air after a pressing operation has been completed. The top and bottom plates are united by a peripheral steel band which is welded to the plates, the band being indicated at 21 and the welds at 21a. The buck is secured to the frame of the pressing machine in known manner by bolts passing through 20 bolt holes in the base 10, one of which is indicated at 22.

Welded or otherwise secured to the bottom plate 14, in air- and steamtight fashion, are two horizontally spaced reinforcing steel beams 23 and 24 which forward unsupported end 15a of the top member, and preferably also to the opposite rearward end 15b. Partition walls 25 and 26 between the beams enclose a vacuum chamber 27, while the wall 26 also bounds a steam chamber 28. A steam inlet port 29 passes through the bottom plate between the beams, and the beams are provided each with one or more passageways 30 for steam to pass to the other sides of the beams and for the return of condensate. As shown in FIG. 1 at 13 and 31, the steam and condensate return pipe 16 is welded to plate 14 about port 29.

The interior space of the top member is divided by a horizontal partition 32 into a steam space 33 and a vacuum space 34. I prefer to make the top surface of the horizontal partition between the steam and vacuum spaces flush with the top surfaces of the beams; and to facilitate welding of the partition to the beams by affording more convenient access to the joints, it is desirable to make the partition of four parts, namely, the part 32 which overlies the steam space 33, and the parts 32a, 32b and 32c which are welded to the band 21. The partition may, however, be made of one piece and overlie the beams, and be connected thereto by screws or the like, metal or other gaskets being employed to insure tightness. In any case, an opening 36 is provided in the partition to afford communication between the vacuum spaces 18 and 34.

The steam supply tube 17 housed within the post terminates at the bend 35 of the post, the steam travelling through the upper portion of pipe 16 which leads into the space 33. The steam and condensate return to the boiler through the upper portion of pipe 16 and the annular space between pipe 16 and tube 17, and are withdrawn through a suitable fitting.

The partition 32 or its several parts may rest on and be welded to the beams 23 and 24 and also on spacer blocks 37 (before the band 21 is applied), and in turn supports spacer blocks 38 which support the top plate 19. It is provided with an opening registering with the vacuum chamber 27 and leading into vacuum space 34. The wall members 11a, 11b and 11c of the post are welded to the bottom plate 14 and also to the walls 25 and 26, thereby providing a strong and rigid support for the buck top member 15.

The post with its pipe 16 and tube 17 pass through a suitable opening in the base 10, the vacuum space 18 communicating with a vacuum chamber 39 from which a pipe 40 leads to the vacuum pump (not shown) associated with the pressing machine. The pipe 16 and tube 17 pass through the bottom wall of chamber 39 and are connected by a suitable two-passageway fitting (not shown) with the boiler.

The buck may be about 8 $\frac{1}{4}$ to 8 $\frac{1}{2}$ inches long, and (at its edges) is about 1 $\frac{1}{2}$ to 1 $\frac{1}{4}$ inches thick. The steel beams absorb the shock when the head of the pressing machine is dropped on the buck and are preferably of solid steel about one-half inch high.

The steam supply tube may have an internal diameter of about five-sixteenths inch and an outside diameter of about three-eighths inch. The return pipe has an I.D. of one-half inch and is preferably of stainless steel.

It will be noted that the post is curved or bent to such a degree toward the opposite end of the buck that the inner or front surface of the bend is substantially vertically below the vicinal rearward outer edge of the top member of the buck, the post being secured to the base 10 over an area which extends beyond, i.e. rearwardly, of the vertical projection of the buck on the base. The post may extend about 2½ inches rearwardly of the region of connection of pipe 16 with bottom plate 14, so that adequate space is provided below the top member, and without obstruction by the post, for the gathering and turning of the garment being pressed. The arrangement of the post at one end of the top member 15, and the forward bend in the post, make it possible conveniently to shift the garment from one pressing position to another without removing it from the top plate. The main portion of the coat or jacket lies away from the top plate, and the fabric on the inside of the garment about the arm holes can thus be pressed, after the lining has been sewed on, without interference from bunching of the garment below the top member.

With my improved buck, the operator can press the left and right sleeves in succession and does not have to remove the garment from the buck after pressing the material about the armhole of one sleeve in order to position it for operating on the armhole fabric of the other sleeve.

It will be seen from the foregoing that I have provided a cantilevered buck which is composed of strong steel plates and beams which are themselves reinforced and rendered more rigid by the partition walls. The steam has free access for contact with the partition walls and the spacer blocks and also with the vertical band 21, so that heat is rapidly conveyed to the top plate and thence, through the usually employed metal wire screen and padding (not shown), to the garment being pressed. Because the vacuum space extends over the whole area of the underside of the top plate, the garment is rapidly cooled and dried at the end of the pressing operation when the steam supply is cut off and the buck connected with the vacuum line after the head of the machine has been lifted.

While I have indicated that various parts are welded to each other, it will be evident that a number of parts can be produced in the form of integral steel castings. However, I have found that a buck built up of welded cold-rolled steel plate and beams has adequate strength to resist the shocks to which the buck is subjected in use.

The post is heat insulated in known manner with an asbestos covering which is secured to the post by a suitable cement, such as a silicate glue; being known, the covering has not been illustrated on the drawing.

As shown in FIG. 1, the post may taper from its base to the bend therein and may taper also at its upper part to a horizontal dimension which is somewhat smaller than at the bend.

I claim:

1. A pressing machine buck comprising a base, a hollow top member having a perforated top plate, and a hollow post connected to the base and to the top member adjacent to an end of said member, said top member being cantilevered on said post, said post containing separate passageways for the supply of steam, for the return of steam and condensate, and for the suction-induced flow of cooling air, said buck having therein horizontally spaced partitioning beams extending longitudinally of the top member to the forward end thereof, an intermediate wall connected to said beams, the bottom wall of said member having a port opening into the space encompassed by said beams and intermediate wall, the steam and condensate return comprising a pipe debouching into such port, a horizontal partition wall sealed to the beams and to the intermediate wall at a distance from the bottom to provide a steam chamber, ports in the beams for the passage of steam and of condensate, and spacer blocks separating the said horizontal partition wall from the perforated top plate and supporting the latter to provide a vacuum space with which the vacuum space in the post communicates.
2. A buck according to claim 1, wherein the post is constituted of the pipe providing the steam and condensate return passage, sidewalls sealed to and extending rearwardly from the pipe, and a transverse wall connecting the other ends of said sidewalls, said sidewalls diverging rearwardly, so that the horizontal cross section of the post is of approximately triangular shape, with the said pipe forming the forwardly directed vertex of the triangle.
3. A buck according to claim 2, wherein the post is bent forwardly intermediate its ends to such a degree that the post is secured to the base over an area extending rearwardly of the vertical projection of the buck on the base.
4. A pressing machine buck comprising a base, a hollow top member having a perforated top plate, and a hollow post connected to the base and to the top member adjacent to an end of said member, said top member being cantilevered on said post, said post containing separate passageways for the supply of steam, for the return of steam and condensate, and for the suction-induced flow of cooling air, the interior of the top member being provided with spaced steel beams extending from approximately the juncture of the post with said member to the opposite end of said member, a transverse wall connecting the beams at the said juncture, and a second transverse wall joining the beams at a distance from the first transverse wall, whereby the space between is divided into two chambers, the steam pipe debouching into one of said chambers and the vacuum space of the post communicating with the other chamber and with the space immediately beneath the perforated top plate, and means for sealing said chambers from each other.
